UNITED STATES PATENT OFFICE.

MAMIE E. ROHR, OF LYNCHBURG, VIRGINIA.

DESIGN FOR A PURSE.

Application filed April 18, 1925. Serial No. 13,158. Term of patent 3½ years.

To all whom it may concern:

Be it known that I, MAMIE E. ROHR, a citizen of the United States, residing at Lynchburg, county of Campbell, State of Virginia, have invented a new, original, and ornamental Design for a Purse, of which the following is a specification, reference being had to the accompanying drawing, forming a part thereof.

I claim:

The ornamental design for a purse, as shown.

MAMIE E. ROHR.
